FIG. VI

UNITED STATES PATENT OFFICE.

RUSSELL H. BOWEN, OF PHILADELPHIA, PENNSYLVANIA, ASSIGNOR TO THE AMERICAN PULLEY COMPANY, OF PHILADELPHIA, PENNSYLVANIA, A CORPORATION OF PENNSYLVANIA.

JOURNAL-BOX.

1,101,831.

Specification of Letters Patent. Patented June 30, 1914.

Application filed January 5, 1912. Serial No. 669,557.

To all whom it may concern:

Be it known that I, RUSSELL H. BOWEN, of Philadelphia, in the county of Philadelphia and State of Pennsylvania, have invented certain new and useful Improvements 5 in Journal-Boxes, whereof the following is a specification, reference being had to the accompanying drawings.

One object of my invention is to permit 10 the construction of a journal box from relatively light sheet steel of substantially uniform thickness throughout, the characteristic structural features, about to be described, being obtained by pressing the sheet 15 metal into the proper shape. The purpose of said structural features is to insure the proper strength, especially at certain critical regions, with a minimum amount of metal in the shell of the journal box, and also to 20 permit self-adjustment of the parts to the extent desirable. Hence the box or casing, in itself, is relatively light in weight, while still possessing all the endurance which has heretofore been sought to be obtained by 25 the use of much heavier metal structures intended for the same general purpose. The parts can be economically constructed and readily assembled, and, when combined, afford the most desirable conditions for self- 30 adjustment of the parts.

Referring to the drawings, Figure I, represents a top or plan view of a journal box embodying my invention, a portion of the shaft or journal being also indicated in this 35 as well as the other figures. Fig. II, is a vertical longitudinal section through the axis of the box. Fig. III, is a top or plan view of the lower member of the box with the upper member removed. Fig. IV, is an 40 end view, in elevation. Fig. V, is a transverse vertical section on the line V, V, of Fig. I. Fig. VI, is a transverse vertical section on the line VI, VI, of Fig. I.

The external casing of the box comprises 45 a lower element 1, and an upper element 2, the former of which, for purpose of convenience, may be termed the trough, and the latter the cover. Each of these elements is preferably made of an integral piece of

sheet metal of substantially uniform thickness, and since the details of the configuration are intended to be attained by pressing the metal into the desired shape, it will be noted that protuberances upon one face correspond with recesses upon the other. The 50 side walls of the trough 1, extend upward somewhat beyond the horizontal axial plane of the journal or shaft 4, as shown in the sectional views, and are rectilinear at their upper edges. Throughout a considerable 55 region adjacent to the longitudinal center of the trough the walls are substantially vertical, as shown at 11, in Figs. IV, and V, said vertical portions however, having a rounded configuration where they merge 60 into the bottom portion 12, which is generally horizontal at said central region. The extremities of the trough adjacent to each end of said straight walls 11, are approximately semi-cylindrical, as shown at 13, in 65 Fig. IV, the ends being turned inwardly, as shown at 14, and terminating in semi-circular apertures 15, of appropriate diameter to receive the shaft 4.

At the regions where the vertical walls 11, merge into the semi-cylindrical end portions 75 13, outwardly projecting channels 16, are formed, extending across the bottom of the trough, so as to afford oil receptacles, to supply the usual oiling rings 5. The bottom of the trough at the region 12, intermediate between these channels is generally horizontal, but has, at its central region, a horizontal annular inward projection 17, within which there is a horizontal annular 80 outward depression 18, surrounding a circular recess in the exterior of the bottom, which recess forms a corresponding rounded 85 internal projection 19.

Within the trough 1, is seated the internal 90 lower shell 3, which is semi-cylindrical throughout the greater portion of its length, and is provided with relatively wide lateral flanges 31, along its upper edges, adapted to fit loosely within the walls of the trough 1. 95 Said lower shell is constructed integrally of sheet metal of substantially uniform thickness, and since its details of construction are

attained by pressing the metal into shape, it will be noted that as in the instance of the casing, protuberances upon one face correspond to depressions upon the other. At 5 the region adjacent to the longitudinal center of said shell, an externally projecting depression 32, is formed in the bottom thereof, said depression being provided with a central circular inward projection 33, whose 10 recessed under surface conforms to the proximate surface of the rounded projection 19, upon the trough 1, and is adapted to rest freely thereon, so as to be capable of a slight rocking motion, while maintaining its general position relatively thereto. Said depression 32, is extended upward on each side of the central region of the shell, but, as it approaches the upper edge, it is bifurcated, forming elongated outward projections 34, 15 and 35, and an intermediate inward projection 36, at each side. Semi-circular openings 38, are formed at intervals corresponding to the positions of the oil receptacles 16, so as to permit the passage of the oiling rings 5.

20 When the shell 3, is placed in position in the trough 1, the bearing surfaces between these two members are the parts 33, and 19, adjacent to the central region of each thereof, and since there is a slight play between 25 the flanges 31, and the internal surfaces of the walls 11, the shell 3, can adjust itself within certain limits by the rocking play of the bearing surfaces.

The cover 2 (also made integrally of sheet metal of substantially uniform thickness), is generally of semi-cylindrical form, of less diameter than the trough 1, and having laterally projecting rectilinear flanges 21, along each edge, of such extent as to fit 30 loosely within the walls of the trough. Said flanges terminate at a distance from each extremity, about equal to the thickness of the end walls of the trough 1, as shown at 35 26, so that the ends of the cover are flush with those of the trough. The cover is formed with externally projecting semi-annular channels 22, corresponding in location to the openings 38, in order to receive 40 the oil rings 5, and has at its central region an externally projecting dished portion 23, at whose center is a circular inwardly projecting rounded recess 24. Said recess 24, and the corresponding rounded recess 19, in 45 the bottom of the trough 1, are adapted to 50 form seats for the ends of the set screws by which the journal box is held at top and bottom. Oil holes 25, are provided in the channels 22.

The cover 2, and the internal shell 3, are 55 provided with linings 40, and 41, respectively, of Babbitt metal, or other suitable material, which are cast into such shape as to fit closely within the interior of each of these parts, so that said linings although re-

movable, are retained in position at the 65 longitudinal central region by the several protuberances and depressions above described as characteristic of the cover 2, and shell 3. The configuration of these linings at the various regions is shown clearly in 70 the sectional views Figs. II, V, and VI, it being also noted that if desired, the cover 2, and the internal shell 3, may be formed with holes 6, and 7, respectively, into which lugs 43, and 44, of the linings may extend, so as 75 to retain said linings in position. The Babbitt metal or other similar lining material, is high in compression strength, and as it is seated in the various depressed portions of the internal shell which are adjacent to the 80 central region, it assists the resistance to collapsing pressure, at the critical points of application of the set screws which clamp the box in position in the hanger.

Having thus described my invention, I 85 claim:

1. In a journal box, the combination of a trough having at the bottom of its longitudinal central region a rounded internal projection; an internal lower shell formed 90 integrally of sheet metal of substantially uniform thickness, provided with lateral flanges along its upper edges, adapted to fit within the walls of the trough, and having at the bottom of its longitudinal central region, an inwardly projecting rounded recess, 95 said recess being surrounded by an externally projecting corrugation having bifurcated extensions on each side, which extend upwardly toward the flanges; a cover having at its longitudinal central region an inwardly projecting recess, and adapted to fit upon the lower shell; and bearing pieces 100 whose external surfaces correspond with the protuberances and depressions situated at 105 the longitudinal central region of the lower shell and cover respectively.

2. In a journal box formed of sheet metal of substantially uniform thickness, the combination of an external lower trough having 110 at its ends upwardly extending semi-annular flanges, and at the bottom of its longitudinal central region, an inwardly projecting recess, forming a rounded internal projection; an annular outward projection surrounding 115 said recess, and an annular inward projection surrounding said outward projection; a lower shell formed integrally of sheet metal of substantially uniform thickness having lateral flanges adapted to fit within the 120 trough, and having, at the bottom of its longitudinal central region, an inwardly projecting rounded recess adapted to bear upon the rounded internal projection of the trough, and having also an outward projection 125 surrounding said recess and extended upward in each side of the shell; a cover adapted to fit within the trough, and having

at its longitudinal central region an inwardly projecting recess; and bearing pieces whose external surfaces correspond with the protuberances and depressions situated at 5 the longitudinal central region of the lower shell and cover respectively.

In testimony whereof, I have hereunto

signed my name at Philadelphia, Pennsylvania, this third day of January, 1912.

RUSSELL H. BOWEN.
